ROAD SCRAPER

Application filed September 3, 1929. Serial No. 390,099.

The invention relates to road scrapers of that type comprising a transversely extending beam which is adjustable to different angles on the main frame of the machine and which carries a scraper connected thereto through the medium of a rock shaft. It is the object of the present invention to provide a simple construction of means for operating the scraper to raise or lower it and to hold it into work under suitable pressure, but yieldably so as to permit the riding over obstacles too rigid to be removed. It is a further object to absorb vibrations and shocks so as to relieve the machine from objectionable stresses. With these objects in view the invention consists in the construction as hereinafter set forth.

In the drawings:

Figure 1 is a plan view showing a portion of the main frame of my improved scraper and operating mechanism mounted thereon;

Figure 2 is a rear elevation;

Figure 3 is an end elevation showing one of the pneumatic cylinders and its connection with the rock shaft;

Figure 4 is a similar view showing a modified construction, and

Figure 5 is a section through the control valve.

In the present state of the art road scrapers have been constructed in which the scraper is mounted upon the frame of a motor driven truck through the medium of a transversely extending beam adjustably clamped in different angular positions. My improvement embodies these general features of construction and as shown A are the sills of a motor truck of any suitable construction; B are posts clamped to these sills and depending therefrom and C are guide segments which are vertically adjustably clamped upon the posts B and which form a support for the transversely extending beam D. These segments are arcs of a circle having its center in the center of the truck and therefore the beam may be adjusted to any angle to which it is desired to arrange the scraper blade. The beam D is secured to the segment C by clamps E as shown.

The beam D is preferably formed of an

inverted channel bar having its web portion clamped to the segments C and its flanges depending. To this channel bar are attached depending bracket members F which form journal bearings for a rock shaft G. The shaft G is preferably formed in two sections G' and G² which are centrally connected to each other by a stepped joint H having sufficient lost motion to permit of limited independent rotation of the shaft sections. The shaft sections G' G² are provided with bracket arms I for attaching the same to the scraper blade J. These bracket arms are preferably formed of a series of leaves I' to impart a slight degree of resilient flexibility thereto which permits one portion of the blade to move differentially from other portions. This is further permitted by the lost motion in the joint H so that it is possible for one end of the scraper to assume a somewhat different angle from the opposite end thereof, this being permitted by the flexibility of the blade.

For raising and lowering the blade and for holding it to its work I have provided pneumatic operating devices which are arranged adjacent to opposite ends of the beam D and are connected to the rock shaft sections G' G². These operating devices consist of a cylinder K and piston L which are arranged intermediate a bracket M extending upward from the beam D and a rock arm N on the rock shaft G. As shown in Figure 3, the cylinder K is pivotally attached at its upper end to the bracket M while the lower end of the rod of the piston L is pivotally connected to the rock arm N. In Figure 4 the reverse arrangement is shown where the piston rod is pivotally attached to the bracket and the cylinder is pivotally attached to the rock arm. With both constructions whenever there is a relative movement of the piston and cylinder to increase the length of the link connection this will rock the shaft G so as to lower the scraper blade and hold it in work. On the other hand, when there is a relative movement of the piston and cylinder which contracts or shortens the length, the rock shaft will be rotated in the opposite

direction to lift the scraper blade out of working position.

The fluid for operating the piston and cylinder is preferably compressed air which 5 may be supplied by any suitable pump such as O mounted in any convenient location on the truck and operated by the truck motor or by any suitable means. The air compressed by this pump is preferably stored in tanks P 10 which may be conveniently mounted above the segments C on opposite sides of the frame bars A. The air is conducted to these tanks through a conduit Q leading from the pump as shown diagrammatically in Figure 1. 15 Connected to the tanks or to the conduit Q is a conduit R leading to the control valve S. This valve is adapted to alternatively connect the conduit R with branch conduits R' and R'', the former leading to the outer ends 20 of the cylinders and the latter to the inner ends thereof. These conduits include flexible hose connections T, T', T'' which lead from the portion of the conduit mounted on the truck frame to the center of the beam D 25 from which point the several conduits extend longitudinally in the channel of the beam to the cylinders at opposite ends thereof. For controlling pressure which is transmitted to the cylinders I preferably arrange 30 a control valve U in the conduit R leading to the outer end of the cylinders which will variably restrict the flow of air and therefore regulate the pressure. I also preferably arrange two other control valves U' and U'' in 35 the branches R' and R'' of the conduit R' which connect respectively to the hose connections T and T' and which lead to the cylinders on opposite ends of the beam. Thus I am enabled to regulate either simultaneously 40 the pressure on both cylinders or independently the pressure on the cylinders at opposite ends.

With the construction as described, in operation when it is desired to transport the 45 scraper without performing any work, the valve S is adjusted into position where air is admitted from the conduit R to the conduit R'' leading to the inner ends of the cylinders, thereby contracting the combined length of 50 cylinder and piston, rocking the arms N upward and withdrawing the scraper blade from contact with the road. To throw the blade into work the valve S is turned to a position where the conduit R is connected 55 with the conduit R' which through the branch conduits R' and R'' transmits air to the outer ends of the two cylinders. At the same time the conduit R'' is connected by the valve S to an exhaust conduit R''' permitting the escape of air from the inner ends of the cylinders. This will lower the blade into work 60 but its speed of movement and also the pressure under which it operates may be regulated by the valves U, U' and U''. Thus if it is 65 desired to have a low pressure on both cylinders

ders the valve U is adjusted to restrict the conduit R' producing that effect. On the other hand, if it is desired to have a higher pressure in one of the cylinders than in the other, this may be regulated by relatively 70 adjusting the valves U' and U''. After the blade is adjusted to its working position it is obvious that it is yieldably held so that any obstacle which offers a resistance in excess of the air pressure in the cylinder will 75 overcome this air pressure and permit the raising of the blade. This is true of either cylinder and therefore the opposite ends of the blade may move independently of each other. This is further facilitated by the lost motion connection between the shaft sections G' and G'' which is sufficient for any relative adjustment desired. 80

My construction has various advantages, one of which is that it requires no operating fluid other than air which is always available and this is not altered in character by temperature conditions and is unlimited in supply. A further advantage is that the air cushion forms the best possible spring or resilient backing for the blade so that the latter will automatically adjust itself to road conditions. 85

What I claim as my invention is:

1. In a road scraper, the combination with 95 a vehicle frame, of a beam mounted on said frame to extend transversely thereof and to be adjustable to different angular positions, a rock shaft journaled in bearings upon said beam and formed in a plurality of aligned sections having a lost motion torque connection with each other, a flexible scraper blade, arms connecting said scraper blade with the respective sections of said rock shaft, and a plurality of pneumatic motors, one for each section of said rock shaft adapted to resiliently and yieldably rock the same, each of said pneumatic motors comprising a cylinder, a piston, a bracket on said beam connected to the one and a rock arm on the rock shaft section connected to the other, and means on the vehicle frame for controlling said motors. 100

2. In a road scraper, the combination with 110 a vehicle frame, of a beam mounted on said frame to extend transversely thereof and to be adjustable to different angular positions, a rock shaft journaled in bearings upon said beam and formed in a plurality of independently rockable aligned sections, a flexible 115 scraper blade, arms connecting said scraper blade with the respective sections of said rock shaft, a plurality of pneumatic motors, one for each section of said rock shaft adapted to independently resiliently and yieldably rock the same, and means on the vehicle frame 120 for controlling said motor. 125

In testimony whereof I affix my signature.
H. EUGENE PRICE.
